Dante's R. Reed, Fort Lauderdale, Fla.

Application January 26, 1945, Serial No. 117,624

Term of patent 14 years

(Cl. D34—13)

To all whom it may concern:

Be it known that I, Dante's R. Reed, a citizen of the United States, residing at Fort Lauderdale, in the county of Broward and State of Florida, have invented a new, original, and ornamental Design for Playing Card, of which the following is a specification, reference being had to the accompanying drawing forming part thereof.

I claim:
The ornamental design for a playing card, as shown.
